UNITED STATES PATENT OFFICE.

HARVEY GILES, OF BROOKLYN, NEW YORK, ASSIGNOR TO ARTEMAS WARD, OF NEW YORK, N. Y.

COIN-CONTROLLED VENDING MACHINE.

1,420,834.

Specification of Letters Patent. Patented June 27, 1922.

Application filed June 3, 1918. Serial No. 237,855.

To all whom it may concern:

Be it known that I, HARVEY GILES, a citizen of the United States, and a resident of Brooklyn, in the county of Kings and State 5 of New York, have invented certain new and useful Improvements in Coin - Controlled Vending Machines, of which the following is a specification.

The invention pertains more particularly 10 to coin-controlled vending machines for the sale of confections, and it resides in the novel features, structure and combinations of parts hereinafter described, and particularly pointed out in the claims.

15 Vending machines of the class to which my invention pertains are provided with trays adapted to receive vertical columns or stacks of the pieces of confection or the like to be sold, and some of these machines have 20 trays containing four side by side compartments for the pieces of confection and others have eight side by side compartments for the confections, and other machines have different numbers of compartments in the 25 trays thereof.

One purpose of my invention is to economize in the space occupied by vending machines and the expense incident to the replenishing of the trays thereof, and to this 30 end I provide a machine, of the width of the ordinary four column machine, having two sets of compartments placed back to back and occupying, if I make use of eight of the compartments, the customary width 35 of a four column machine. The tray having the eight vertical compartments for the columns of confections to be sold, these compartments being placed back to back, four being at the front and four at the rear, affords the capacity of an eight column machine and, as distinguished from a four column machine, requires to be replenished no 40 more frequently than an eight column machine would be required to be replenished, whereby the expense of attending to the 45 machines is reduced and the machines themselves occupy very much less space than eight column machines require and can be used in locations where an eight column machine could not conveniently be located.

My invention comprises coin-controlled mechanism for the sale of the confections from the duplex trays and also means whereby after the lowest piece of confection has 50 been sold from each or any of the rear trays,

the succeeding sales are made from the front trays until the front trays have been emptied, and thereafter if the machine is continued in operation, as will be usual, the pieces of confection will be sold from the 60 rear trays until those trays have become emptied, and thereafter an attendant may replenish both sets of trays with confections for further sales from the machine.

The coin-controlled mechanism of my invention comprises goods ejectors for the two sets of trays and means, on the introduction of the proper coins into the machine, for the manual operation of said ejectors for displacing the goods and causing them to fall 70 upon a chute whereby they are directed to the purchaser. The coin-controlled mechanism of my invention comprises various features and details of construction, all of which will be better understood from the 75 specific explanation thereof hereinafter presented.

My invention also comprises means for the protection of the trays and coin-controlled mechanism, as well as the coins in 80 the coin box, from the rough treatment to which coin-controlled vending machines located in public places are subjected in attempts to open the machines for the purpose 85 of removing the coins and confections therefrom.

The invention will be fully understood from the detailed description hereinafter presented, reference being had to the accompanying drawings, in which:

Fig. 1 is a front elevation of a coin-controlled vending machine embodying my invention;

Fig. 2 is a vertical section of the same, taken on the dotted line 2—2 of Fig. 1, with 95 all of the interior parts in normal position, the section being only through the cabinet and delivery chute;

Fig. 3 is a vertical section, on an enlarged scale, on the dotted line 3—3 of Fig. 7, with 100 the interior mechanism shown in normal position ready for operation;

Fig. 4 is a vertical section, taken on the dotted line 4—4 of Fig. 7, a part of the interior mechanism being omitted and that 105 shown being intended more particularly to illustrate the means for locking the vending mechanism in position and the coin box door in closed position, said door however being in this figure shown in its open position;

Fig. 5 is a detailed sectional view, taken on the dotted line 5—5 of Fig. 4;

Fig. 6 is a further detailed section, taken on the dotted line 6—6 of Fig. 4;

5 Fig. 7 is a horizontal section through the machine, taken on the dotted line 7—7 of Fig. 3, all of the mechanism being shown in normal position ready for use;

10 Fig. 8 is a front elevation, partly broken away and partly in section, of the lower portion of the machine, the interior mechanism being illustrated in front elevation, and the lower front covering plate of the machine being omitted;

15 Fig. 9 is a transverse section through the tray for holding confections, looking downwardly and taken on the dotted line 9—9 of Fig. 11;

20 Fig. 10 is a bottom view of the tray for holding confections;

Fig. 11 is a rear elevation, partly broken away, of the tray, this figure showing more particularly the lower portion of the tray; and

25 Fig. 12 is a detail section through a portion of the lower part of the tray, taken on the dotted line 12—12 of Fig. 11;

In the drawings, 30 designates the exterior casing of the machine as a whole, said casing comprising a back 31, sides 32, a top 33, a bottom 34, a lower front portion 35 and a removable front or door 36. In rear of the door 36 is formed a chamber for the tray, numbered as a whole 37, for holding the 35 stacks or vertical columns of confections, and within the lower portion of the casing is formed a chamber for the operative mechanism of the machine and also for a coin-receptacle 38 which receives the coins after 40 they have left the operative mechanism and from which the coins may be removed when desired and after the hinged back and bottom 39 of the receptacle has been unlocked to swing downwardly and rearwardly or to 45 the position in which it is shown in Fig. 4. At the rear of the coin box or receptacle 38 is provided a chute 40 down which the pieces dislodged from the tray may slide to an opening 41 below the front section 35 of 50 the casing and from which opening said pieces may be removed by hand.

Above the chamber enclosing the operative mechanism is a substantially horizontal covering plate or frame 42 whose edges are 55 adapted to guide in grooves 43 formed in the sides 32 of the main casing, as indicated in Fig. 1. The rear portion of the plate or frame 42 is formed with a depressed seat 44 for the lower edge of the front door 36, and rearwardly of said seat 44 the plate or frame 42 is equipped with upwardly extending plates 45 which aid in locating the lower edge of the door 36 upon said seat and which plates may be formed integrally with a 60 metal plate 46 which covers the main bottom

portion of the plate or frame 42, which I preferably make of wood, and said plate 46 is formed with a downwardly extending front flange 47 to aid the same in protecting the wooden covering frame or plate 42 and 70 also in forming an exterior housing for the upper edges of a coin slot plate 48 hereinafter referred to. The sides 32 of the main casing are provided in line with the seat 44 with inwardly projecting pins or studs 49 75 adapted to fit recesses 50 formed in the lower outer edges of the door 36, said recesses being formed in a metal covering strip applied to the sides and lower edge of said door, and said pins or studs 49 being formed on metal 80 plates 51 (Fig. 4) secured to the inner surfaces of the sides 32. When the covering plate or frame 42 is slid to position along the guiding slots or recesses 43, the door 36 is placed upon the seat 44 and the recesses 85 50 in said door are lowered downwardly upon the studs or pins 49, and thereupon the upper end of the door 36 is secured to the top 33 of the casing by means of a suitable lock 52. When the door 36 is locked 90 in position it prevents the withdrawal of the covering plate or frame 42, and at the same time said covering plate or frame 42 conceals the lower end of the door 36. When the door 36 is unlocked and lifted 95 outwardly at its upper end and becomes released from the pins or studs 49, the covering plate or frame 42 may be slid outwardly from the grooves 43.

Upon the upper edge of the lower front 100 portion 35 of the main casing is rigidly secured a horizontal shelf 53, which may be of wood, and upon the rear side of said portion 35 is secured a series of plates 54 having concave recesses at their upper edges to serve 105 as seats for the reciprocating plunger rods 55, four of which are made use of in the machine illustrated, said rods 55 being the operating rods for the machine. The plates 54 are integral with a transverse metal plate 56 110 clearly shown in Fig. 3.

The space between the forward lower portion of the covering plate or frame 42 and the shelf 53 is covered by a vertical coin-slot plate 48 which will be of metal and have a 115 series of coin-slots 57 in its upper portion, and at its upper edge said plate 48 is located in rear of the aforesaid front flange 47 formed on the metal plate 46. The flange 47 serves to protect the upper edge of the 120 plate 48. The lower portion of the plate 48 extends downwardly behind the shelf 53 and is slotted to straddle the aforesaid plates 54, said plate 48 at the upper ends of its said slots being recessed, as at 58, to transversely encompass the plunger rods 55, said rods being thus transversely enclosed between the upper ends of the plates 54 and the recesses 58 of the plate 48. The plate 48 at its opposite side edges is held between 130

metal plates 59 which are secured to the sides of the main casing and have vertical ribs 60 to engage the front of the side edges of said plate 48, and the plates 59 are also 5 formed with projections 61, 62 in rear of the rib 60 to engage the rear of the side edges of the plate 48, said plate 48 being thus held by the ribs 60 and projections 61, 62 against movement frontwardly or rearwardly, but being permitted at the proper time and on the removal of the front frame 10 42 to be slid upwardly from the machine.

The tray 37 is of special construction in that among other features it is composed of 15 a plurality of auxiliary sections 75 (each intended for a column of confection) placed back to back and connected together, the main tray in the present instance comprising four front sections 75 and four rear sections 20 75, and the several sections both at the front and rear being connected together, in the usual manner, to form a substantially integral structure; and in addition the front and rear sections 75 are secured together at 25 their upper and lower ends, the upper ends of said front and rear sections being connected by plates 76 (Fig. 2) and the lower ends of said front and rear sections being secured together by end plates 77, also shown 30 in Fig. 2. The front and rear series of sections 75 are separated throughout the greater portion of their length by a space 78, and the front series of sections 75 open frontwardly and the rear series of said sections 35 open rearwardly, and both series of sections are formed at their open sides with inwardly extending flanges 79, 80, respectively, to retain the columns of confections within said sections, the pieces of confection 40 being numbered 81. The flanges 79, 80 are of known type, and likewise the pieces of confection 81 are of usual character. At their opposite lower edges the several sections of the tray 37 are provided with 45 flanges 82, also of known character, for supporting the columns of confection at the end edges of the pieces thereof, and the flanges 82 at the lower ends of the sides of the main tray may be formed by flanging the plates 50 77 inwardly below the front and rear adjacent sections 75, while the flanges 82 for the intermediate sections 75 may be formed integrally with a connecting and supporting plate 83 which is at the front of the 55 main tray 37 and has members extending inwardly below the adjoining edges of the adjacent trays 75, which members afford the lateral flanges 82 to receive the end edges of the lower pieces of confection 81. The 60 flanges 82 are usual in trays for slot machines and in themselves do not constitute features of novelty. I preferably form the end-plates 77 integrally with the plate 83 and rearwardly extending members which 65 afford the flanges 82, but these parts may be

made in separate pieces should that be desired. At the rear side of the lower portion of the tray 37 I connect the series of rear sections 75 by means of a plate 84, this plate serving to additionally connect the series 70 of rear sections 75 together, and at the lower edge portion of the plate 84 I secure a rod 85 upon which are hinged a series of independent plates 86, there being one plate 86 for each rear section 75, and said plate normally extending downwardly in rear of the upper portion of the lower pieces of confection in said rear sections 75. In Figs. 3, 11 and 12 I show the plates 86 in their normal position, and these plates are not only 80 hinged on the rod 85, but by means of small coiled springs 87 (Figs. 9, 10, 11) are given a normal tension yieldingly maintaining them in their normal vertical position, shown in Figs. 3 and 10. The plates 86 are less in 85 length than the width of the rear tray sections 75, as shown in Fig. 10, and they do not extend downwardly entirely to the lower ends of said tray sections, the partitions between which extend downwardly to and 90 preferably enter slots in the rear ends of the members of the plate 83 which afford the lateral flanges 82, as shown in Figs. 10 and 11, in which, for convenience, I number said partitions as 88. The hinged plates 86 turn 95 rearwardly and upwardly under the pressure of a piece of confection being ejected and then immediately return to their vertical position, so as to prevent the jarring out of any additional pieces of confection or the 100 carrying out of an upper piece of confection by friction contact with a lower piece being ejected. The spring plates 86 are all independent of one another, and hence the action of one plate 86 has no effect on the 105 other plates 86.

Between the lower ends of the front and rear sections of the tray 37 I secure a rod 89, and on this rod 89 are loosely hinged or hung a series of plates each having two lips 110 or fingers 90, one being at each side of each tray section 75 and directly above the flanges 82 (Fig. 9) supporting the columns of confections. In the normal condition of the machine, when installed and loaded with the 115 confections, the fingers 90 extend downwardly between the front and rear tray sections 75, as shown in Fig. 3, and the lower ends of the fingers 90 lie between the front and rear lower pieces of confection in said sections, 120 and in such position perform no special duty. The fingers 90 for each rear tray section 75 are separated from each other by a space at least equal to the width of a goods ejector, so that a goods-ejector may pass between them, but the said space between said fingers 90 is less than the length of a piece 125 of confection 81. One novel feature of the tray 37 is to provide the front and rear tray sections 75 and equip the same with means 130

whereby after the bottom piece of confection in a rear section 75 has been sold, all of the subsequent sales shall primarily be from the related front section 75 until said front tray section has been emptied, and to this end I provide the pairs of fingers 90, one pair being at the front of the lower end of each rear tray section 75.

- I may explain here that I employ two goods ejectors numbered 91, 92, respectively, for each pair of front and rear tray sections 75, and that the ejector 91 serves to displace the successive pieces of confection from the front tray section 75 and move the same to the bottom of the rear tray section 75, and that the ejector 92 dislodges the pieces of confection from the bottom of the rear tray sections 75 so that they may slide down the aforesaid chute 40 to the delivery opening 41.
- 20 The pieces of confection held in the front tray section 75 are not sold therefrom directly, but are successively displaced therefrom, by the goods ejector 91, to the bottom of the rear tray section 75, from which they 25 are successively discharged by the goods ejector 92, this operation taking place until the front tray section 75 has been emptied, whereupon the goods ejector 91 will travel idly back and forth at each operation of the 30 machine and the rear goods ejector 92 will effect the dislodgement of the successive pieces of confection in the rear tray section 75 until said section has been emptied, and thereupon both the front and rear tray sections 75 will be replenished.

One novel feature of the front tray sections 75 is that the lower ends of the front flanges 79 thereof are bent rearwardly, as at 93, and these rearwardly inclined portions 40 of said flanges 79 result in the bottom piece of confection 81 in the front tray sections being normally displaced slightly rearwardly, as shown in Fig. 3, thus slightly offsetting the bottom piece of confection in the 45 front tray section 75 from the piece immediately above it, and one advantage of this feature is that the goods ejector 91 is permitted, with greater assurance, to engage the bottom piece of confection and move it rearwardly 50 without disturbing the piece of confection immediately above said bottom piece.

The front tray sections 75 are equipped with weights 94 of customary character to rest upon the column of confections therein, 55 and said weights are concaved at their lower ends, as usual, so that after all of the pieces of confection in a front tray section 75 have been sold, the goods ejector 91 may continue its movements with the rear goods ejector 92 without interference from said weight. The rear column sections 75 are also equipped with weights (Fig. 3), numbered 95, to press upon the columns of confections in said rear sections 75, and said weights 95 60 are of special construction, as shown in Fig.

3, in that they are provided with pivoted latch plates 96 mounted within slots 97 formed in said weights. The weights 95 are also provided with light springs 98 which normally press downwardly upon the front 70 operative ends of said latch plates 96. The latch plates 96 are formed at their rear ends with stop shoulders 99 to limit the downward movement of the front ends of said plates, and the front ends of said plates are formed 75 with hooks 100 adapted to catch upon the rear goods ejectors 92 when any of said ejectors has been moved rearwardly and dislodged the final piece of confection from a rear tray section 75, the engagement of said 80 hook with said goods ejector 92 being automatic, due to the gravity of the latch plate 96 and the action of the spring 98, and serving to lock said goods ejector 92 and the parts connected therewith, in their 85 rear inoperative position. The locking of the goods ejector 92 and parts connected therewith in their rear inoperative position when the rear tray section 75 has been emptied, also results in the plunger rod 90 intended for such rear tray section being locked in its inner position, so that until the time for replenishing said rear tray section, said plunger rod is inoperative.

The tray 37 as a whole is held in position 95 upon stationary arms 101 extending upwardly from the mechanism of the machine and entering holes in the supporting or bracket plate 83 and also by screws 102 which also extend upwardly from the mechanism of the machine and receive upon their heads the lower end of the tray between the rear sections 75 thereof, there being two of the screws 102 made use of and two of the vertical arms 101, as shown in Fig. 7. The 105 upper ends of the arms 101 are of reduced width and hence afford shoulders, as shown in Fig. 7, to support the bracket plate 83, which, as hereinbefore explained, is rigid with the tray 37.

110 The coin box or receptacle 38 comprises the aforesaid combined back-and-bottom 39, pivotally secured at its upper rear opposite end edges upon side screws 103, side plates 104 secured to the sides of the main casing, a forward top section 105 and a lower front angle-plate 106, which plate 106 is pivotally secured, as at 107, and is spring pressed forwardly, by springs 108, in a direction from the lower edge of the hinged bottom 120 39, so that when the said bottom 39 is to descend, as for the discharge of the coins, the plate 106 will turn forwardly and permit said bottom to fall downwardly against the chute 40, or to the position shown in Fig. 125 4. When the hinged bottom 39 is in its upper operative position, the lower flange of the plate 106 extends below the front edge of said bottom 39 and serves to aid in locking said bottom in secure closed position, as 130

shown in Fig. 3. The hinged plate 106 is locked in its closed position by means of vertically slidable latch bars 109, there being one of these bars 109 adjacent to each side 5 of the machine and close against the side plates 104 of the coin box. The bars 109 are, at their lower ends, formed with slots 110 which receive screws 111 and permit of the vertical movement of said bars 109 on said 10 screws. The bars or plates 109 may also have a pivotal movement to a limited extent on said screws 111. Above their lower ends the bars or plates 109 are given a spring tension rearwardly by means of small coiled springs 15 112, the springs 112 serving to pull the upper portions of the bars or plates 109 against stop pins 113 extending toward each other from the side plates 104 of the coin box, and adjacent to the pins 113 the latch bars 109 20 are formed with shoulders 114 which cooperate with the pins 113 in locking the latch bars in their lower operative position, shown in Fig. 3, and holding the plate 106 in its closed position. In Fig. 4 I illustrate the 25 latch bars or plates 109 in their upper inoperative position, in which position they permit the angle plate 106 to be turned to its open position by means of the springs 108. The extreme upper portions of the bars or 30 plates 109 curve rearwardly, as at 115, and afford handles by which said bars may be pulled upwardly or pressed downwardly.

The plate 106 is formed at its lower opposite side edges with laterally projecting 35 arms 116 (Fig. 8), and these arms are at the rear of the lower ends of the latch bars or plates 109 when said plates are in their lower position shown in Fig. 3, and in this relation of the parts the plates 109 serve to 40 lock the angle plate 106 in its closed or operative position shown in Fig. 3 supporting and concealing the front edge of the hinged bottom plate 39 of the coin receptacle. When the latch plates 109 are pulled upwardly so 45 as to clear the arms 116, the springs 108 will turn the angle plate 106 to its open position, shown in Fig. 4, and then the bottom plate 39 will turn downwardly and permit the coins thereon to slide downwardly to the 50 discharge opening 41. In the use of the latch bars or plates 109, their upper ends 115 are, when it is desired to release the angle plate 106, drawn forwardly so as to carry the shoulders 114 of said plates from under the 55 pins 113 and then said plates 109 are lifted upwardly to the position shown in Fig. 4. When it is desired to lock the angle plate 106 in its closed position, the latch plates 109 are pushed downwardly and then turned 60 rearwardly so as to carry the shoulders 114 below the pins 113 or to the position shown in Fig. 3. The latch plates 109 cannot be manipulated from the front opening 41, because they cannot be pushed upwardly by 65 reason of the engagement of the shoulders 114 with the pins 113, and they cannot be turned forwardly so as to carry said shoulders from said pins, because the coin slot plate 48 has, on its rear side, pins or studs 117 which, when said coin slot plate is positioned, stand close against the front edges of the upper portions of said latch plates and bind said plates in their operative position.

Whenever it is desired to remove the coins 75 from the coin receptacle, the front 36 of the main casing must be removed and then the shelf 42 must be withdrawn so as to release the coin slot plate 48, and thereupon the coin slot plate will be elevated from the casing and thus expose the latch plates 109 so that they may be released from the pins 113 and pulled upwardly or to the position shown in Fig. 4, for the purpose of releasing the angle plate 106 from the bottom 39 of 80 the coin receptacle.

The top 105 of the coin receptacle is inclined downwardly and forwardly and may be utilized as a means for returning improper coins to the purchaser, said coins 85 falling downwardly on the chute 40 and appearing at the delivery opening 41.

The top 105 of the coin receptacle is inclined downwardly and forwardly and may be utilized as a means for returning improper coins to the purchaser, said coins 90 falling downwardly on the chute 40 and appearing at the delivery opening 41.

That portion of the machine which may be designated as the mechanism and which is located above the coin receptacle, may be 95 handled as a unit and is shown in top view in Fig. 7 and front elevation in Fig. 8, and this mechanism comprises a stationary main supporting plate 118 having a downwardly turned rear end 119 and at its front end 100 having secured thereto a vertical plate 120 and a small upwardly and rearwardly inclined plate 121. The plate 118 supports the operative mechanism and is secured in position upon shoulders 122 (Fig. 4) at the upper edges of the sides 104 of the coin receptacle. The plate 118 has at opposite sides of about its middle side portions downwardly turned ears 123 (Fig. 4) and these ears carry pins 124 adapted to be hooked 105 into rearwardly opening slots 125 of bracket plates 126 which extend upwardly from the aforesaid shoulders 122, as shown in Figs. 4 and 5. The plate 118 adjacent to the opposite side edges of its front portion has downwardly extending ears 127 at whose lower front edges are outwardly bent flanges 128 (Fig. 6) which are adapted to be engaged by fingers 129 formed on the lower ends of vertically slidable latch plates 130, these 110 plates 130 being slotted and secured to the sides of the main casing and vertically movable. When the plates 130 are pushed downwardly their fingers 129 pass in rear of the flanges 128 and then serve with the aforesaid pins 124 to lock the mechanism in operative position, with the ears 123, 127 resting upon the aforesaid shoulders 122. The front shelf 42 of the main casing is directly 115 over and conceals the latch plates 130, and 120

125 125 130

hence said plates cannot be operated to release the mechanism until said shelf 42 has been withdrawn. When the shelf 42 is withdrawn from the machine and the latch plates 130 are pulled upwardly, so as to release the ears 127, the attendant may by first pushing the mechanism rearwardly to free the pins 124 from the bracket plates 126, lift the mechanism out of the main casing 10 for such attention as it may require.

For each plunger rod 55 at each coin slot there is, below the main supporting plate 118, a stationary plate 131 and a sliding plate 148 respectively carrying the coin-controlled devices, the plunger rod being fastened to the plate 148 and said plate being movable with said rod, which rod and plate are normally held in their outer or forward position by a coiled spring 151 and are returned to such position by said spring after 20 the plunger and plate have been moved inwardly either in the act of selling a piece of confection or idly.

Upon the upper side of the main supporting plate 118 for the mechanism, I provide for each plunger rod 55 and consequently for each coin slot, a back-and-forth sliding plate 170, these plates being alike and lying flat upon the upper surface of the supporting plate 118 and parallel with one another. The plates 170 carry the goods ejectors 91, 92 hereinbefore referred to, these ejectors being of sheet metal and having ears extending downwardly from the opposite sides 30 thereof and which are pivotally secured between corresponding ears turned upwardly from the edges of the plates 170. The goods ejectors 91, 92 incline downwardly and forwardly, being overweighted at their forward portions, by reason of which said ejectors normally take an operative position. The means, on the introduction of the proper coin to the machine, for moving the plates 170 and the goods ejectors carried by 40 them rearwardly to operate the machine, consists of the lip or finger 162 on the bell-crank plate 155 and a downwardly extending side member 171 integral with each of said plates 170 and projecting downwardly 45 through slots 172 in the main top plate 118 and having at their lower ends a fork 173 between whose vertical fingers or members the lips 162 of the plates 155 normally stand, as shown in Fig. 3. When no coin is fed to 50 the machine or an improper coin, and the plunger rod 55 is pressed inwardly, we have already seen that when the plate 155 leaves the stop 140, its lip 162 will turn downwardly under the force of the spring 160, 55 and this notwithstanding the fact that the said finger or lip 162 initially stands between the two members of the fork 173, and said fork will not be actuated at such time. When 60 however a proper coin is introduced to the machine and a plunger 55 is pushed in-

wardly, the lip or finger 162 of the plate 155 will press against the rear member of the fork 173 and at the same time ride along above a shelf or guide not shown, and through said fork and plate 171 cause the 70 related slide 170 to move rearwardly and carry the goods ejectors 91, 92 against the lower pieces of confection as above described.

The plates 170 are guided in their forward and backward movements by means of slots 174 cut in said plates and screws 175 which pass downwardly through said slots and engage the main top plate 118. I form ratchet teeth 176 on side edges of the plates 80 170 and pivot pawls 177 on the plate 118 in position to engage said ratchet teeth when a plate 170 is moved rearwardly. I connect each pair of pawls 177 by means of a small coiled spring 178 which serves to keep the 85 pawls spring-pressed against the ratchet teeth 176 and to turn said pawls to normal position at right angles to the plates 170 when said plates are at their full rear position or at their full front position. 90

The operation of the several features of the machine have been pointed out hereinbefore to a sufficient extent to render an elaborate further detail description of such operation unnecessary. Each plunger rod 95 55 and the mechanism connected therewith is a duplicate of each of the other plunger rods and the cooperating mechanism thereof.

When the plates 170 are moved rearwardly on the sales of the confections, said plates 100 pass rearwardly beyond the rear edge of the main supporting plate 118, and the dislodged pieces of confection may fall on the rear ends of said plates 170 when said plates are in their rear position, but such pieces 105 will not be carried back into the machine on the return frontward movements of the plates 170, because said plates move frontwardly between rigid vertical flanges 200 which are spaced apart a distance less than 110 the length of a piece of confection and serve to strip, whenever necessary, a piece of confection from the plates 170 on the return frontward movement of said plates.

What I claim as my invention and desire 115 to secure by Letters-Patent, is:

1. In a coin-controlled vending machine, in combination, a general casing, a vertical tray therein having front and rear sections for stacks of confections, goods-ejectors for 120 said sections, one ejector for ejecting the bottom piece of one stack and the other for displacing the bottom piece of the other stack to the bottom of the first mentioned stack, and a manually operative rod for 125 effecting a sale on the introduction of a coin, to the machine.

2. In a coin-controlled vending machine, in combination, a general casing, a vertical tray therein having front and rear sections 130

- for stacks of confections, goods-ejectors for said sections, one ejector for ejecting the bottom piece of one stack and the other for displacing the bottom piece of the other 5 stack to the bottom of the first mentioned stack, and a manually operative rod for effecting a sale on the introduction of a coin to the machine, said tray having between the lower ends of said sections hinged members adapted on the ejection of the first bottom piece from the first mentioned stack to be folded up under the other pieces of said stack under the pressure of the displaced piece from the other stack to said first 10 mentioned stack.
3. In a coin-controlled vending machine, in combination, a general casing, a vertical tray therein having front and rear sections for stacks of confections, goods-ejectors for said sections, one ejector for ejecting the bottom piece of one stack and the other for displacing the bottom piece of the other 15 stack to the bottom of the first mentioned stack, a manually operative rod for effecting a sale on the introduction of a coin to the machine, said ejectors being pivoted and overweighted at one end to tilt downwardly on their forward movement below the stacks of confections and thereafter automatically return to operative position with relation to said stacks. 60
4. In a coin-controlled vending machine, in combination, a general casing, a vertical tray therein having front and rear sections for stacks of confections, goods-ejectors for said sections, one ejector for ejecting the bottom piece of one stack and the other for displacing the bottom piece of the other 20 stack to the bottom of the first mentioned stack, a manually operative rod for effecting a sale on the introduction of a coin to the machine, and said tray having between the lower ends of said sections hinged members adapted on the ejection of the first bottom piece from the first mentioned stack 25 to be folded up under the other pieces of said stack on the displacement of the bottom piece from the other stack to said first mentioned stack.
5. In a coin-controlled vending machine, in combination, a general casing, a vertical tray therein having front and rear sections for stacks of confections, goods-ejectors for said sections, one ejector for ejecting the bottom piece of one stack and the other for displacing the bottom piece of the other 30 stack to the bottom of the first mentioned stack, and a manually operative rod for effecting a sale on the introduction of a coin to the machine, said ejectors being pivoted and overweighted at one end to tilt downwardly on their forward movement below the stacks of confections and thereafter automatically return to operative position with relation to said stacks. 65
6. In a coin-controlled vending machine, in combination, a general casing, a vertical tray therein having front and rear sections, arranged back to back, for stacks of confections, goods-ejectors for the respective 70 sections, and manually operative means for, on the introduction of a coin to the machine, actuating said ejectors to eject the bottom piece of one stack and displace the bottom piece of the other stack to the bottom of the 75 first mentioned stack, whereby after the said bottom piece of the first stack has been ejected the sales will be of the pieces originally contained in said other stack until all thereof have been disposed of, after which 80 the pieces in the first stack will be sold.
- Signed at New York city, in the county of New York and State of New York, this 24th day of May A. D. 1918.
